HENRY J. MEYER, OF WAUKESHA, WISCONSIN, ASSIGNOR TO I. B. ROWELL CO., OF WAUKESHA, WISCONSIN

COMBINATION FEED CUTTER AND HAMMER MILL

Application filed September 4, 1928. Serial No. 303,803.

This invention relates to a combination feed cutter and hammer mill.

Objects of this invention are to provide a novel machine which combines a feed cutter and hammer mill with means for receiving the comminuted feed and material from the hammer mill which thoroughly mixes and delivers such feed to a fan which, in turn, delivers the thoroughly mixed material wherever desired.

It is a well known fact that a recutter and a hammer mill both must operate at a high rate of speed to effectively function, and it is also apparent that several high speed devices mounted in one machine and separately driven will eventually cause considerable vibration for the entire machine.

This invention is designed to overcome the defects noted immediately above, and further objects of this invention are to provide a machine which combines a rapidly rotating feed cutter, hammer mill, and fan, and has a single shaft for each of these instrumentalities, so that absolute balancing and freedom from vibration, together with a marked simplification in the driving mechanism is obtained.

An embodiment of the invention is shown in the accompanying drawings in which:

Figure 1 is a fragmentary side elevation of the combined machine;

Figure 2 is a sectional view on the line 2-2 of Figure 1;

Figure 3 is a sectional view on the line 3-3 of Figure 2;

Figure 4 is a sectional view on the line 4-4 of Figure 2.

Referring to the drawings, particularly Figure 1, it will be seen that roughly the usual construction of feed cutting machine is followed. The machine comprises a feed cutter shaft 1 and a recutter shaft 2, upon which are carried the pulleys 3 and 4, respectively.

These pulleys are driven by means of the belt 5, or in any other suitable manner, and preferably an idler pulley 6 is provided to secure the requisite grip of the belt around the pulleys 3 and 4.

The shaft 1, as may be seen from Figures 1 and 2, is provided with a sprocket wheel

7, which drives by means of a chain a sprocket wheel 8. The sprocket wheel 8 is rigidly attached to sprocket wheels 9 and 10, which respectively drive a sprocket wheel 11 mounted upon the conveyor shaft 12 and a sprocket wheel 13 mounted upon a short stub shaft 14. The stub shaft 14 carries a small gear 15 which is in mesh with a second small gear 16. Both of these gears are carried upon a rocking frame 17 which is controlled by the pivot lever or hand lever 18. Either gear 15 or 16 may be thrown into mesh with a gear 19 mounted upon the shaft 20 hereinafter described.

The shaft 20 drives in any conventional manner, not shown, the shafts 21, 22, and 23. The shafts 20 and 21 carry the feed rollers 24 and 25, the roller 25 being floating. The shaft 22 carries the upper roller 26. The shaft 23 carries the drive roller for the conveyor 27 which brings the feed to the cutter in the usual manner. Immediately adjacent the roller 14, the cutter bar 28 is positioned.

The floating of the shafts 21 and 22 is readily accomplished by means of the tension bars 29 (see Figure 1) which are located on opposite sides of the machine and which are drawn downwardly by means of the spring-pressed rods 30.

Referring to Figure 3, it will be seen that the shaft 1 carries the cutter 31, which cooperates with the cutter bar 28 in the usual manner. Immediately below the cutter, a recutter 32 is positioned and is carried upon the shaft 2. This recutter is mounted within a casing 33 which is provided with a plurality of apertures 34 from which the comminuted feed may pass. A downwardly converging receiving casing 35 is positioned immediately below the recutter and receives the comminuted feed therefrom.

The casing 35 extends across the bottom of the machine and houses the screw conveyor 36. This casing 35 is positioned below the bottom apertured portion 37 of the hammer mill. This hammer mill has the rotary member 38 provided with a plurality of hammer heads 39. Each of these hammer heads, as may be seen from Figure 4, is pivotally mounted and carried by pins which, in turn, 100

are carried by the discs forming the rotor 38. The heads may be reversed or changed, end for end, so that four active corner portions may be employed to thus prolong the life of these heads. The material for the hammer mill is supplied by means of an adjustable chute or hopper 40 (see Figures 1, 3, and 4). This hopper discharges directly into the main casing 41 of the hammer mill.

10 It is to be noted that the casing which encloses the conveyor extends completely across the bottom of the machine and terminates in a tubular portion which is connected by means of the pipe 42, which leads to the suction end of the fan casing 43. The discharge portion or chute of the fan casing is indicated by the reference character 44 and may be connected with a silo or any other desired point. Within the fan casing, a rotary fan 45 is positioned.

15 It is to be noted, particularly from reference to Figure 2, that the recutter 32, the hammer mill rotor 38, and the fan 45, are all mounted upon the same shaft, indicated by the reference character 2, and previously described. This shaft, it will be noted, is supported adjacent each end and intermediate its ends, that is to say, between the rotor of the hammer mill and the recutter. It is, therefore, possible with this construction to minimize the vibration of the entire machine.

20 It is also apparent that it is easier to balance up the machine than where three separate high speed instrumentalities are employed. Instead of this, these three high speed instrumentalities, namely, the recutter, the hammer mill, and the fan, are all rigidly carried by a firmly supported main shaft.

25 It is also apparent that the screw conveyor 36 insures a thorough mixing of the comminuted feed with the material discharged from the hammer mill, as it passes the comminuted feed below the hammer mill, and thus the material from the hammer mill is dropped in a uniform manner upon the passing comminuted feed.

30 Thereafter, this mixture is delivered to the fan and through the action of the fan is carried to the desired point in a thoroughly mixed condition.

35 It will be seen further that a relatively simple machine has been provided which has extreme compactness, which is free from delicate or easily damaged parts, and which instead, is extremely sturdy and reliable in operation.

40 Although the invention has been described in considerable detail, such description is intended as illustrative rather than limiting as the invention may be variously embodied and as the scope of such invention is to be determined as claimed.

I claim:

45 1. In a machine of the class described, the combination of a cutter, a recutter mounted

below said cutter and adapted to comminute material discharged from said cutter, a hammer mill coaxial with said recutter, said hammer mill and recutter having the same shaft, and means mounted below said hammer mill and recutter for receiving, mixing and delivering material discharged from said hammer mill and recutter.

50 2. A combination feed cutter and hammer mill comprising a feed cutter, a recutter located below said feed cutter, a hammer mill having a rotary portion mounted upon the shaft of the recutter, a fan comprising a casing having an inlet and an outlet portion and having a fan mounted upon the recutter shaft, a conveyor located below the recutter and hammer mill, and a pipe connecting the discharge end of the conveyor with the inlet portion of the fan, whereby different materials may be comminuted and thoroughly mixed and delivered by said fan through its discharge portion.

55 3. In a machine of the class described, the combination of a cutter, a recutter mounted below said cutter and adapted to comminute material discharged from said cutter, a hammer mill coaxial with said recutter, and means mounted below said hammer mill and recutter for receiving, mixing and delivering material discharged from said hammer mill and recutter.

60 In testimony that I claim the foregoing I have hereunto set my hand at Waukesha, in the county of Waukesha and State of Wisconsin.

65 HENRY J. MEYER.
